UNITED STATES PATENT OFFICE.

EDWARD ELLIS, OF MINNEAPOLIS, MINNESOTA.

BILL-FILE.

1,109,053.

Specification of Letters Patent.

Patented Sept. 1, 1914.

Application filed October 13, 1913. Serial No. 794,826.

To all whom it may concern:

Be it known that I, EDWARD ELLIS, a citizen of the United States, residing at Minneapolis, in the county of Hennepin and State of Minnesota, have invented certain new and useful Improvements in Bill-Files, of which the following is a specification.

My invention relates to bill files, and more particularly to that class of bill files having a body portion or card adapted to receive advertising matter and means for hanging the same in proper position, and a file hook secured to the card.

It is the object of my invention to provide a bill file of this character which shall be particularly simple in construction and in which the file hook is adjustably secured to the card so that the same may be laid flat upon the card for shipping purposes and yet readily drawn into operative position when desired.

It is also an object of my invention to provide means on the card coöperating with means on the file hook for holding the same rigidly in position when drawn into operative position.

The full objects and advantages of my invention will appear in connection with the detailed description thereof and are particularly pointed out in the claims.

In the drawings, illustrating the application of my invention in one form, Figure 1 is a perspective view of a bill file embodying my improvements when the file hook is in operative position. Fig. 2 is a plan view of such a bill file with the file hook laid flat for shipping. Fig. 3 is a detail view of the file hook. Fig. 4 is a plan view of the rear side of the card or pad portion showing a modification. Fig. 5 is an enlarged sectional view on line 5—5 of Fig. 1.

The body portion or card 10 may be of cardboard or metal of any suitable weight and may have any desired printed matter upon the face thereof, an eyelet 11 being provided for hanging the card in position. The lower portion of the card is provided on the face thereof with a reinforcing pad 12 which may consist of cardboard, cloth or any other desired substance. Upon the rear of the body portion 10 in similar position to pad 12 another pad 13 may, if desired, be employed, the two pads being secured to the said body portion 10 by gluing or also by means of an eyelet 14. It may

not be necessary or desirable to employ pads on both sides of the body portion 10, and pad 12 on the front side or pad 13 on the rear thereof may be employed separately without departing from the spirit of my invention.

The file hook comprises a suspending shank 15, an angularly offset portion 16, and a pointed hook portion 17 extending back nearly parallel with the shank portion 15. At the free end of the shank portion 15 is formed a hook-like member 18, in appearance something like a shepherd's crook, having a depressed point 19 approaching the shank 15, and an outwardly curved extremity 20.

In addition to the eye 14, through the card 10 and the pads 12 or 13 or both, a hole 21 is provided extending through the cardboard 10 just below or at the outer edge of said pad or pads. The file hook is assembled upon the pad by inserting the pointed end 17 through eye 14, first from the face end of the pad and back again through the hole 21. The angular portion 16 is then passed through the two holes and the shank 15 brought to extend through the eye 14 and hole 21.

For shipping at the factory the file hook is laid over upon the face of the card, as indicated in Fig. 2, where it occupies but little space, so that the bill file may be packed together in very compact form. When it is desired to assemble the file hook in operative position this is done by merely turning same so that the shank 15 and hook 17 are in a plane perpendicular to the card and drawing the shank outwardly until the hook-like portion 18 comes outside of the pad 12, the depressed portion 19 gripping the pad and card, and the crook engaging the eye 14, all as indicated in Fig. 5. The depressed portion 19 will be to some extent forced into the body of the pad or cardboard which it engages, resulting in holding the file hook firmly in a plane at right angles to the plane of the card 10. When the bill file thus assembled is hung up by means of the eye 11 the hook 17 will be held extended outwardly in proper position to receive bills or slips.

It will be apparent that my bill file is extremely simple, cheap to manufacture, easy to ship and handle, may be readily assembled for use by a single movement, and

when so assembled is efficient and satisfactory to a high degree.

In the modification shown in Fig. 4, back pad 13 is triangular and has a hole adjacent to its upper edge passing through the card only. A projection 22 may be formed at the bottom of the card through which passes a hole 21.

It is obvious that there are various different modifications of structure possible in making this bill hook which should be included in my invention. In the manufacture of this article it is probable that the form of my invention which is the most inexpensive to construct, simple to assemble and efficient in use would be adopted.

I claim:

1. A bill file comprising a card, a pad secured to a portion of said card, said card being provided with holes adjacent the inner and outer edges of the pad in the central line of the card, and a file hook having a shank extending through said holes and a hook portion on said shank engaging the pad to hold the shank and the file hook in operative position.

2. A bill file comprising a card, a pad secured to a portion of said card, said card being provided with holes adjacent the inner and outer edges of the pad in the central line of the card, and a file hook having a shank extending through said holes and a hook portion on said shank engaging the pad to hold the shank and the file hook in operative position, said file hook having all parts thereof in a common plane and having the shank thereof extending through the said holes so that the hook thereon may be disengaged from said pad and the file hook may be laid flat upon the card and will be held within the margin thereof when the bill files are packed for shipping.

3. A bill file comprising a card, a pad secured to a portion of said card, said card being provided with holes adjacent the inner and outer edges of the pad in the central line of the card, and a file hook having a shank extending through said holes and a hook portion on said shank engaging the pad to hold the shank and the file hook in operative position, said shank having an outwardly turned end and a depressed

portion for gripping the card and pad between the same and the shank.

4. A bill file comprising a card adapted to receive advertising matter thereon, means at one end for suspending the card, a pair of pads secured at opposite sides of the other end of the card along the central line thereof, a hole being provided through said pads and card adjacent the inner edge of the pads, and a file hook having the shank thereof extending through said hole and having a hook-like member at the end of the shank gripping the pads between the shank and said member to hold the file hook in a plane perpendicular to the plane of the card.

5. A bill file comprising a card, a pad secured to a portion of said card, said card having holes adjacent the inner and outer edges of said pad, and a file hook having a shank extending through said holes and a hook portion on said shank engaging the pad to hold the shank and the file hook in operative position.

6. A bill file comprising a card, a pad secured to a portion of said card, said card having a hole adjacent the inner edge of said pad, and a file hook having a shank extending through said hole and a hook portion on said shank engaging the pad to hold the shank and the file hook in operative position.

7. A bill file comprising a card adapted to receive advertising matter thereon, means at one end of the central line of the card for suspending the card, a pad at the other end of the card along the central line thereof, said card being provided with a hole in said central line of the card adjacent the inner edge of the pad, and a file hook having the shank thereof extending through said hole and having a hook-like member at the end of the shank gripping the pad and card between the shank and said member to hold the file hook in a plane perpendicular to the plane of the card.

In testimony whereof I affix my signature in presence of two witnesses.

EDWARD ELLIS.
